GLASS SCORING MACHINE

John S. Harker, Vineland, N. J., assignor to Kimble Glass Company, Vineland, N. J., a corporation of Illinois

Application December 6, 1941, Serial No. 421,981

10 Claims. (Cl. 49—48)

The present invention relates to apparatus for scoring cylindrical glass ware, and more particularly to mechanism for feeding, positioning, and rotating the ware with respect to suitable scoring means.

Certain materials used by surgeons and physicians, such as ligatures and the like, are stored in sterile glass containers until ready for use. These containers are provided with a circumferential score to permit the container to be broken when it is desired to remove the contents thereof. The containers are usually bottomed at one end and open at the other end to permit insertion of the material. After they have been filled, the containers are sealed tightly. It has been found expedient to employ an unbreakable seal so that breakage of the container along a circumferential line or score intermediate its ends is the customary manner in which the container is opened to remove its contents.

This invention has to do primarily with providing a circumferential score mark on containers of the character referred to, the mark being incised at a predetermined distance from an end of the container.

Another object of the invention is so to sort or position the containers before scoring that the closed ends thereof will always be aligned on the same side of the cutting saw.

Still another object of the invention is the provision of timed mechanism designed to feed, sort and score the containers so that these operations are all done automatically in predetermined sequence.

The invention will be further understood from the accompanying drawings in which:

Fig. 1 is a side elevation of a preferred embodiment of a machine for feeding, sorting and scoring cylindrical glass ware;

Fig. 2 is a rear sectional elevation of the machine taken on line 2—2 of Fig. 1, parts thereof being removed for clarity;

Fig. 3 is a partial front elevation of the machine;

Fig. 4 is a partial top plan view of the machine;

Fig. 5 illustrates the cams employed on one cam shaft;

Fig. 6 illustrates the cams on another cam shaft, one of the cams being broken away;

Fig. 7 is a front view of one of the cams shown in Fig. 6;

Fig. 8 is a perspective of a reversing mechanism employed in the machine;

Fig. 9 is a partial elevation of one of the transfer bars used to advance the ware;

Fig. 10 is a section through a transfer plate taken on line 10—10 of Fig. 2; and

Fig. 11 is a longitudinal section taken on line 11—11 of Fig. 3.

5 In the drawings, the base frame 11 is supported on legs 12. Brackets 13, 14 are also secured to legs 12 and carry bearings 15, 16 for cam shaft 17 and cross rod 18, respectively. Brackets 19 on the frame support posts 21 to which are secured 10 brackets 22, 23 in which are mounted rods 24, 25 supporting feed racks 26 and magazine 27, respectively.

Magazine 27 comprises a pair of parallel side walls 28, the forward ends of which are of reduced height, and an L-shaped plate 29 having a vertical portion 31 and an inclined portion 32, the latter being parallel to an inclined bottom member 33 of the magazine. The plate 29 is vertically adjustable to space the portion 32 a distance from member 33 sufficient to permit only one layer of the glass blanks 20 disposed in the magazine to roll toward the discharge end of the magazine. A second bottom member 34 is positioned somewhat higher than member 33 and is bent downwardly at 35 to meet member 33. An agitator 36 insures feeding of the blanks onto member 33. At the discharge end of the magazine is a vertically oscillatable gate 37, operated by cam and link mechanism to be described hereinafter, which permits release of the blanks one at a time.

20 Feed racks 26 are moved rearwardly by a step-by-step mechanism, including cam 20 on shaft 17 and lever 20' pivoted on rod 18, the containers released by gate 37 being deposited one at a time in successive notches 38 of the rack. When a predetermined number of blanks has been deposited in the notches, the rack is moved in the opposite direction sufficiently forwardly to bring the rack notches into vertical alignment with similarly spaced channels in plate 39, the latter at this time being positioned in a plane below that of the rack notches.

25 Referring to Figs. 1 and 2, it will be seen that a number of cams are fast on shaft 17. Cam 40, also shown in Fig. 6, engages roller 41 on rocker arm 42 pivoted on cross rod 18. Secured to arm 42 is an arm 42' which, through link 43, oscillates gate 37. Cam 44, shown in Fig. 6, controls the elevation and lowering of plate 39 through arms 45, 45' on rod 18, the arms being fast to each other, link 46 and arm 47 pivoted on shaft 48. Arm 47 carries roller 49 engaging a head 51 on the lower end of post 52, to the upper end of which is secured the plate 39. Post 52 is guided

by bracket 53 and is rotatable as well as vertically reciprocable with respect thereto. A second channeled plate 54, similar to plate 39, is secured to post 55, the latter being guided for vertical reciprocation by bracket 56. At the lower end of post 55 is a head 57 engageable with roller 58 on arm 59, the latter being fast with arm 59' and pivoted on rod 18. Arm 59' is connected by link 61 to arm 62 on shaft 48 and roller 58 on arm 59' engages cam 60 on shaft 17. The operation of the cams and rocker arms for raising and lowering plates 39 and 54 is similar for each of these plates, but the reciprocation is neither simultaneous nor of equal duration or distance for reasons which will be apparent from operations which will be later explained.

Mounted on base frame 11 on opposite sides of the machine are standards 63 having laterally extending arms 64 thereon. Secured to arms 64 are brackets 65 forming supports for spaced parallel guide rods 66. Slidably mounted on rods 66 are sleeves 67 connected at one end thereof by a U-shaped bridge 68 and having secured to their other ends yokes 69. These yokes are connected by links 71 with cross piece 72 of lever 13, the latter being pivoted on bracket 74 bolted to frame 12. The lower end of lever 13 carries roller 75 which engages cam 76. In this way the sleeves and bridge 68 are reciprocated in a direction transverse to movement of racks 26. Secured to bridge 68 are push rods 77, these push rods being in parallel relation and spaced a distance equal to the distance between the channels in plates 39 and 54.

As shown in Fig. 4, the glass blanks 30 are so positioned on plate 39 that the open ends of some of the blanks are nearest certain of the push rods 77. The blanks are deposited transversely in magazine 27 but without regard to the direction in which the open ends of the blanks face, so that, when deposited on plate 39, the open ends of some of the blanks may be nearest push rods 77 while others may have their closed ends nearer the push rods. Hence, when push rods 77 are moved toward the blanks in Fig. 4, they will engage only those blanks the closed ends of which face the push rods to push these blanks over onto plate 54 and will enter the open ends of others of the blanks if such open ends face the push rods. In order to transfer all of the blanks from plate 39 to plate 54, mechanism is provided for turning plate 39 through an angle of 180°. This mechanism comprises a toothed rack 78 guided in bracket 53 and meshing with pinion 79 splined on post 52. Rack 78 is reciprocated by lever 81 pivoted on rod 18, the lower end of the lever carrying roller 82 engageable with cam 83 and the upper end of the lever being connected by link 84 to the rack. In this manner, opposite ends of the blanks are alternately positioned to present the closed ends of the blanks to the ends of the push rods so that successive reciprocations of the push rods will transfer all of the blanks from plate 39 to plate 54.

Fixed to sleeves 67 and parallel to a plane coincident with the ends of push rods 77 is a plate 85 positioned slightly above and forwardly of the ends of the push rods. After the first transfer movement of the push rods, plate 39 is elevated a distance sufficient to permit plate 85 to engage the ends of the blanks remaining on plate 39. While in this elevated position, plate 39 is turned through a half revolution. Plate 85 is then moved forwardly to align the ends of the blanks. This is done to prevent abnormally posi-

tioned blanks from engaging the push rods as plate 39 is lowered to be thereby tilted and perhaps fall into the machine.

After the blanks first engaged by the push rods have been transferred to plate 54, and during the period when plate 39 is being elevated, rotated, and then lowered to a position in which the blanks remaining on plate 39 may be engaged by the push rods, plate 54 is lowered a distance sufficient to permit the blanks, which project beyond the side edges of plate 54, to be deposited on parallel inclined guides 86, these guides being spaced a distance sufficient to permit plate 54 to pass between them. Plate 54 is again elevated to receive the blanks which have been reversed and transferred by the push rods and again lowered to permit these latter blanks to rest on guides 86. The blanks roll down the inclined guides until the forwardmost blank rests against upturned flanges 87 which act as stops. It will be apparent that, after two reciprocations of the push rods, the closed ends of the blanks all face in the same direction. Adjacent to and within guides 86 are spaced parallel notched racks 88, the rear edge of the racks being disposed immediately under and in back of the foremost blank in the guides. Adjacent each of these racks are aligned discs or rollers 89 forming saddles for supporting the blanks so that they may be rotated. It is to be noted that each notch in the rack 88 is defined by a relatively long inclined face 88' and a vertical step face 88''. The racks are mounted on vertically reciprocable slides 91 each having at its lower end a roller 92 engaging cams 93 on cam shaft 94. As the rack is elevated by the cams, the notch nearest guides 86 lifts the foremost blank above the first rollers, the blank rolling down the inclined faces of the racks to be deposited between adjacent rollers, that is, in the first saddle. Successive reciprocations of the racks advance the blanks from one saddle to another and finally discharge the blanks into a suitable container.

When a blank has been deposited between the central pairs of rollers, it is scored. Before the scoring tool engages the ware, however, the blank is properly positioned to insure scoring at a predetermined distance from an end of the blank. Referring to Fig. 3, it will be seen that standard 95 is provided at its upper end with a threaded boss 96 into which is threaded an adjustable stop member 97. At the opposite side of the rollers is a second standard 98 having a boss 99 provided with a plain bore in which there is slidably mounted for reciprocation therein a push rod 101. Spring 102 in the boss bears against a shoulder on the push rod to urge the push rod into engaging relation with the ware. Pivoted to the standard at 103 is a bell crank 104 one arm of which bears against nut 105, the latter being adjustable on a threaded portion of the push rod. The other arm of the bell crank is engaged by a vertically reciprocable rod 106 having a suitable guide bearing in the machine frame. Rod 106 carries roller 107 which rides on cam 108, the latter being fast on cam shaft 94. As the ware is positioned in the appropriate saddle and in line with the push rod, cam 108 permits release of spring 102 and push rod 101, the latter urging the ware against stop 97. In this way the ware is definitely positioned with respect to the cutting tool shown generally at 109.

The cutting or scoring tool disclosed herein is a rotary disc 111 having a sharpened peripheral edge and mounted on a frame 112 pivoted on

shaft 113 to permit movement of the tool toward and from the ware. Frame 112 has an extension 114 having a counterweight 115 suspended from the end thereof. The saw is driven from motor M through belts 116, 117, jack-shaft 118, pulleys 119, 120, and belts 121, 122. It is understood that the tool is swingable about its fulcrum 113, being normally urged upwardly to engage the ware by counterweight 115. It should be noted at this point that cam shaft 17 is driven from cam shaft 94 by means of chain 123. During the step of transferring the ware to the saddles, the tool is lowered by lifting extension 114 and the counterweight suspended therefrom. This is done by cam 124 which engages roller 125 on arm 126, the latter being connected to arm 127, which, in turn, is connected to extension 114 through link 128.

As shown in Fig. 3, a cross rod 129 is supported from the upper ends of standards 63. Pivotedly mounted on this rod is a sleeve 130 having arms 131, 132 fast thereon, arm 131 carrying a yoke 133 in which is journaled a driven pressure roll 134. Arm 132 is connected to lever 135 by link 136. Lever 135 is pivoted on shaft 113 and carries roller 137 engageable with cam 138. Cams 124 and 138 move the scoring tool and pressure roll toward the ware simultaneously to engage the lower and upper sides of the ware, respectively. The pressure roll is positively driven and is provided with a friction surface to rotate the ware while it is being scored. The means for driving the pressure roll consist of chain 139 meshing with sprockets 141, 142 on cam shaft 94 and stub shaft 143, respectively, stub shaft 144, and propeller shaft 145 connected to the stub shafts by universal joints 146.

From the foregoing description it will be seen that cylindrical blanks, each having a closed end, are automatically fed from a hopper or magazine to mechanism which rights the ware to position all of the blanks with the closed ends to one and the same side of the scoring tool. The blanks are then presented one at a time to the scoring tool which scores a circumferential shallow groove in the ware.

The several cams operate the mechanisms herein described to advance the ware through the operating stages of feeding and reversing the ware, positioning it in predetermined relation with respect to the scoring tool and finally scoring the ware. The several operations are all automatic and continuous so that the blanks are scored accurately as well as rapidly.

While a preferred embodiment of the invention has been illustrated and described, it is to be understood that it may be modified to meet varying requirements. The claims are, therefore, to be construed with this in view.

Having described my invention, what I claim as new and desire to secure by Letters Patent is:

1. In a machine for scoring a plurality of cylindrical glass blanks, each having a closed end and an open end, a scoring tool, means for sorting said blanks to position the blanks with the closed ends of all of the blanks in alignment, and means for effecting relative movement of the blanks and the tool to score the blanks.

2. In a machine for scoring a plurality of glass blanks, each having a closed end and an open end, a scoring tool, means for sorting said blanks including a pair of plates for supporting the blanks in spaced parallel relation, means for engaging the closed ends of certain of said blanks to transfer the blanks from one to the other of said plates,

and means for thereafter positioning the transferred blanks in predetermined relation to said scoring tool.

3. In a machine for scoring a plurality of glass blanks, each having a closed end and an open end, a scoring tool, means for sorting said blanks including a pair of plates for supporting the blanks in spaced parallel relation, means for engaging the closed ends of certain of said blanks to transfer the blanks from one to the other of said plates, means for rotating said one plate 180° to present the closed ends of the others of said blanks to said end engaging means whereby said other blanks are transferred to said other plate, and means for thereafter positioning the transferred blanks in predetermined relation to said scoring tool.

4. In a machine for scoring a plurality of glass blanks, each having a closed end and an open end, a scoring tool, means for sorting said blanks including a pair of plates for supporting the blanks in spaced parallel relation, a plurality of spaced reciprocable push rods adapted to engage the closed ends of certain of said blanks, means for positioning the blanks in axial alignment with said push rods, means for reciprocating said push rods to transfer the blanks from one to the other of said plates, and means for thereafter positioning the transferred blanks in predetermined relation to said scoring tool.

5. In a machine for scoring a plurality of glass blanks, each having a closed end and an open end, a scoring tool, means for sorting said blanks including a pair of plates for supporting the blanks in spaced parallel relation, means for engaging the closed ends of certain of said blanks to transfer the blanks from one to the other of said plates, means for rotating said one plate 180° to present the closed ends of the others of said blanks to said engaging means, means for positioning the blanks in axial alignment with said engaging means, means for reciprocating said engaging means to transfer the blanks from one to the other of said plates, and means for thereafter positioning the transferred blanks in predetermined relation to said scoring tool.

6. In a machine for scoring a plurality of cylindrical glass blanks, each having a closed end and an open end, means for sorting said blanks including a pair of members having spaced parallel recesses therein, a plurality of spaced parallel push rods, means for reciprocating said push rods to engage the closed ends of certain of said blanks to transfer said certain blanks from one to the other of said plates, and means for rotating said one plate 180° to position the closed ends of the blanks remaining on said one plate to be engaged by said push rods.

7. In a machine for scoring a plurality of cylindrical glass blanks, each having a closed end and an open end, means for sorting said blanks including a pair of plates, each having spaced parallel channels on one face thereof, the channels in one plate being aligned with the channels in the other of said plates, a plurality of reciprocable push rods, said push rods being parallel and spaced a distance corresponding to the spacing of said channels, and means for reciprocating said push rods to transfer blanks from one to the other of said plates.

8. In a machine for scoring a plurality of cylindrical glass blanks, each having a closed end and an open end, means for sorting said blanks including a pair of plates each having spaced parallel channels on a horizontal face thereof, the

channels in one plate being alignable with the channels in the other of said plates, a plurality of spaced horizontal push rods, said push rods being parallel and spaced a distance corresponding to the spacing of said channels, means for lowering and elevating said plates, means for depositing blanks on one of said plates in one position thereof, and means for reciprocating said push rods to engage blanks on said one plate in another position thereof to transfer the blanks to the other of said plates.

9. In a machine for scoring a plurality of cylindrical glass blanks, each having a closed end and an open end, means for sorting said blanks including a pair of plates each having spaced parallel channels on a horizontal face thereof, the channels in one plate being alignable with the channels in the other of said plates, a plurality of spaced horizontal push rods, said push rods being parallel and spaced a distance corresponding to the spacing of said channels, means for lowering and elevating said plates, means for depositing blanks on one of said plates in one position thereof, means for reciprocating said push rods to engage blanks on said one plate in

another position thereof to transfer the blanks to the other of said plates, and means for rotating said one plate to reverse the ends of the blanks remaining on said one plate.

10. In a machine for scoring a plurality of cylindrical glass blanks, each having a closed end and an open end, means for sorting said blanks including a pair of plates each having spaced parallel channels on a horizontal face thereof, the channels in one plate being alignable with the channels in the other of said plates, a plurality of spaced horizontal push rods, said push rods being parallel and spaced a distance corresponding to the spacing of said channels, means for lowering and elevating said plates, means for depositing blanks on one of said plates in one position thereof, means for reciprocating said push rods to engage blanks on said one plate in another position thereof to transfer the blanks to the other of said plates, gear means associated with said one plate, a rack meshing with said means, and means for reciprocating said rack to rotate said one plate whereby the ends of the blanks remaining on said one plate are reversed.

JOHN S. HARKER.
